UNITED STATES PATENT OFFICE.

ARON BRAUNSTEIN AND ANGEL RATTINER, OF NEW YORK, N. Y.

ANTISEPTIC SHAVING-BRUSH.

No. 829,364.

Specification of Letters Patent.

Patented Aug. 21, 1906.

Application filed April 29, 1905. Serial No. 258,080.

To all whom it may concern:

Be it known that we, ARON BRAUNSTEIN, a subject of the King of Roumania, and ANGEL RATTINER, a citizen of the United States, residents of the borough of Brooklyn, city and State of New York, have invented certain new and useful Improvements in Antiseptic Shaving-Brushes, of which the following is a full, clear, and complete disclosure.

10 The object of our invention is to provide a shaving-brush with a brush portion or member which can be used but once and being impregnated with an antiseptic soap or similar solution will in itself provide the soap for lather.

15 A further object of our invention is to provide means for keeping said brush member antiseptic at all times before being used and after once being used it cannot be used again without the fact of such use being indicated to the subsequent user. We attain this object by the arrangement of parts and construction described in the following specification and shown in the accompanying drawings, forming a part thereof, said specification and drawings showing one embodiment of our invention which at the present time is deemed preferable by us.

20 In the drawings, Figure 1 is a longitudinal sectional view of the brush and its handle, showing the brush member removed from said handle and the envelop or casing also partially removed from the brush. Fig. 2 is a side elevation of our device, showing the arrangement of parts immediately before use. Fig. 3 is a transverse sectional view taken substantially upon the line 3-3 of Fig. 2. Fig. 4 is a detached sectional view of the brush member of the shaving-brush.

25 Referring to the drawings, the letter *f* indicates a suitable handle or holder, in one end of which is a socket or recess *a*, having a spring *b* attached to one side thereof for the purpose of holding the brush member of the 30 shaving-brush removably within the socket *a*. The letter *d* indicates a bunch or tuft of bristles, hairs, or fibers, one end of which is bound together and capped with paper or other similar material, as indicated at *c*.

35 The cap *c* is preferably antiseptically treated, and the bristles or fibers of the brush are impregnated with an antiseptic solution of shaving-soap, which may be either allowed to remain moist or dried be-

fore being sealed or enveloped. The binding-cap *c* is made of paper or similar material which will become softened when water is applied to the brush, and therefore after being used the bristles are no longer held together by the band.

40 The letter *e* indicates a casing or envelop which is adapted to inclose the bristles or fibers of the brush and preferably forms a part of the cap *c* before being removed from the bristles.

45 In the use of our improved shaving-brush the cap *c* is first inserted into the socket *a*, where it is frictionally retained by the spring *b*. The envelop or casing *e* is then torn or cut away, which exposes the bristles or fibers 50 *d*, so that the same may be used immediately by applying water and forming a lather in the usual way.

55 It will be noticed that the bristles, cap, and envelop may be provided as a single article 55 of manufacture, substantially in the form of a cartridge, and a number of these cartridges 60 may be supplied with a single handle or holder.

65 It is our intention that the brush member 65 or cartridge shall be used only once and then thrown away or discarded, and for this purpose the cap and bristles may be manufactured at a small cost.

70 Having thus described our invention, 85 what we claim, and desire to protect by Letters Patent of the United States, is—

75 1. In an antiseptic shaving-brush, the combination with a tuft made of suitable fibrous material and impregnated with an 80 antiseptic composition of soap, a band for binding said tuft together at one end, of an easily-destructible envelop inclosing said 85 tuft and a handle having means for detachably holding said tuft.

90 2. In an antiseptic shaving-brush, the combination with a tuft made of suitable fibrous material and impregnated with an 95 antiseptic composition of soap, a band of paper for binding said tuft together at one 100 end, of an easily-destructible casing or envelop inclosing said tuft, and a handle having means for detachably holding said tuft and envelop.

105 3. In an antiseptic shaving-brush, the combination with a tuft made of suitable fibrous material, and impregnated with an 110 antiseptic composition of soap, a band of

material which softens under the action of moisture for circumferentially binding said tuft together at one end, of a casing or envelop inclosing said tuft only, and a handle having a spring-actuated member for detachably holding said tuft.

4. As an article of manufacture, a brush member for a shaving-brush comprising a tuft of suitable fibrous material, a band of

material which softens under the action of moisture, and an easily-destructible envelop completely inclosing and sealing said tuft.

ARON BRAUNSTEIN.
ANGEL RATTINER.
